HYDRAULIC POWER SYSTEM FOR RECIPROCAL MOVEMENT

Wayne W. McMullen, 1602 67th St., Des Moines, Iowa

Filed July 9, 1962, Ser. No. 208,396

10 Claims. (Cl. 60—51)

My invention relates to hydraulic cylinders, the circuit in which they function, and the controls therefor, whereby reciprocal movement of the cylinders and positive control thereof is achieved. This invention is an improvement of my co-pending application Serial Number 164,944 filed January 8, 1962.

A principal object of my invention is to provide a hydraulic system incorporating a control means and a pair of cylinders interconnected in a pair of separate hydraulic circuits whereby one circuit can support a given load and the other circuit can be used to induce reciprocal movement to the load.

A further object of my invention is to provide a hydraulic power system for reciprocal movement wherein the reciprocal movement can be adjustably varied and controlled.

A still further object of my invention is to provide a hydraulic power system for reciprocal movement wherein movement of the load involved in one direction is slowed, stopped and thence reversed by accumulators within the various hydraulic circuits.

A still further object of my invention is to provide a hydraulic power system for reciprocal movement which can automatically compensate for fluid losses in the load supporting circuit.

A still further object of my invention is to provide a hydraulic power system for reciprocal movement that will provide a smooth transition of power to the load involved as the movement thereof is being reversed to reduce wear on both the power equipment and the components of the load being moved.

A still further object of my invention is to provide a hydraulic power system for reciprocal movement wherein a plurality of loads can be intermittently reciprocated.

A still further object of my invention is to provide a hydraulic power system for reciprocal movement wherein a plurality of loads can be intermittently reciprocated while being located at remote locations.

A still further object of my invention is to provide a hydraulic power system that is economical to manufacture and durable in use.

These and other objects will be apparent to those skilled in the art.

My invention consists in the construction, arrangements, and combination, of the various parts of the device, whereby the objects contemplated are attained as hereinafter more fully set forth, specifically pointed out in my claims, and illustrated in the accompanying drawing, in which:

FIGURE 1 is a vertical sectional view of one of my hydraulic cylinders;

FIGURE 2 is a plan view of one of my cylinders mounted on a derrick structure with the yoke of a pump mounted thereon;

FIGURE 3 is a plan view of another of my cylinders similarly situated as the cylinder in FIGURE 1 but with the hydraulic controls attached thereto;

FIGURE 4 is an elevational view of the cylinders shown in FIGURES 2 and 3 with interconnecting hydraulic conduits schematically arranged;

FIGURES 5, 6, 7 and 8 are partial elevational views of the two cylinders depicted in FIGURE 4 and show the relative positions of the control elements as the

2

two cylinders are in various positions in their reciprocal cycle;

FIGURE 9 is an elevational view of the control means that is actuated when the load supporting circuit becomes depleted of fluid;

FIGURE 10 is a side elevational view of the cam control surfaces on my device;

FIGURE 11 is a front elevational view of the cam control surfaces on my device;

FIGURE 12 is a sectional view through one of my accumulators when the fluid has been exhausted therefrom; and

FIGURE 13 is a view similar to that of FIGURE 12 when the diaphragm of the accumulator has been filled with fluid.

I have used the numeral 10 to generally designate an outer base cylinder comprised generally of a flat bottom portion 12 and vertical side walls 14. Apertures 16 in the protruding edges of bottom portion 12 can be used to facilitate the connection of cylinder 10 to a supporting surface 18.

A vertical bore 20 is located in the center of bottom portion 18 and an upwardly extending shoulder 21 appears at the upper end thereof. Groove 22 is formed at the upper inner periphery of shoulder 21. Bore 20 receives the lower end of vertical shaft 24 which is shaped to rest on groove 22 before terminating in the lower portion of bore 20. Shaft 24 is rigidly secured to cylinder 10 in any convenient manner such as by a threaded connection. A shoulder 28 extends outwardly from shaft 24 at a point just below its upper end. The center bore 29 of a stationary piston 30 receives the extreme upper end of shaft 24 whereby the piston rests on the shoulder 28 of the shaft. A threaded bore 32 appears in the center of the upper end of shaft 24. Shaft 34 has a diameter equal to that of shaft 24. A shoulder 36 similar to shoulder 28 on shaft 24 extends outwardly from shaft 34 at a point just above the threaded lower end of shaft 34. The threaded lower end of shaft 34 is received in the center bore 29 of piston 30 and is threadably received within the threaded bore 32 in the upper end of shaft 24. Thus, the piston 30 is held in a stationary position between the similar shoulders 28 and 36 of two similar shafts 24 and 34, respectively. Shaft 34 extends upwardly from piston 30 and can have stop elements 38 detachably secured to its upper end in any convenient manner.

A movable inner cylinder 40 having an outside diameter substantially equal to the inside diameter of base cylinder 10 is slidably mounted within and projecting from the upper end of cylinder 10. Cylinder 40 is comprised generally of a bottom portion 42 which is connected in any convenient manner such as by threads to vertical side walls 44 and a top portion 46. A flange 48 is secured to and protrudes outwardly from top portion 46 and apertures 50 therein to facilitate the attachment of the flange to an object or component part of related equipment which is to be forcibly moved. A vertical bore 52 in bottom portion 42 of cylinder 40 slidably receives shaft 24. Similarly, vertical bore 54 in the center of top portion 46 of cylinder 40 slidably receives shaft 34. Sealing elements 56 and 58 effect a seal between cylinder 40 and shaft 34; elements 60 and 62 effect a seal between piston 30 and cylinder 40; sealing ring 64 mounted on the upper periphery of cylinder 40 assists in effecting a seal between cylinders 10 and 40, as does sealing ring 66 on the lower end of cylinder 40; and elements 68 and 70 effect a seal between the lower end of cylinder 40 and shaft 24.

As shown in FIG. 1, a hydraulic fluid compartment 72 is formed between the bottom portions of the two cylinders.

ders 10 and 40. A second hydraulic fluid compartment 74 is located between stationary piston 30 and the bottom portion 42 of inner cylinder 40. A third hydraulic fluid compartment 76 is located between stationary piston 30 and the upper portion 46 of inner cylinder 40.

A port 78 in the upper portion 46 of cylinder 40 communicates with passageway 80 which in turn communicates with fluid compartment 76. A port 82 in the bottom portion 12 of cylinder 10 terminates in passageway 84 which in turn registers with passageway 86 in shaft 24. The upper end of passageway 86 communicates with fluid compartment 74. Port 88 in the lower portion of cylinder 10 communicates directly with fluid compartment 72.

In FIGURE 4, I have shown pairs of the hydraulic cylinder just described, and the second cylinder in each of these figures will have the letter "A" following the numeral identification of its component parts so that, for example, shaft 34 in one cylinder will correspond to shaft 34A in the other cylinder. Derricks 90 and 90A, with supporting surfaces or platforms 18, support the cylinders 10 and 10A. The respective cylinders can be secured to platforms 18 by inserting appropriate fastening means through apertures 16 and 16A in the bottom portions of each cylinder. Yokes 92 and 92A respectively include horizontal bars 94 and 94A which are secured to the upper surfaces of cylinders 40 and 40A by bolt and nut assemblies 96. Vertical hanger bars 98 and 100, and 98A and 100A, are secured to the ends of bars 94 and 94A, respectively, and extend downwardly therefrom. The hanger bars slidably extend through suitable openings (not shown) in platforms 18. The lower ends of the hanger bars on each cylinder are joined by couplings 102 which can be operatively connected to an oil pumping mechanism located beneath each derrick. The oil pumping mechanism is associated with an oil well usually located directly below each derrick.

An oil reservoir 104 is mounted in any convenient fashion on the platform 18 of derrick 90A and contains a hydraulic pump 106 which in turn is connected to a convenient source of electrical power or the like (not shown). A conventional switch (not shown) can control the operation of pump 106. A bracket 108 is secured to the top of reservoir 104 and valve means 110 is rigidly secured to the top of the bracket. A conduit 112 connects pump 106 with a pressure port in valve means 110.

Two parallel arms 114 and 116 are pivotally secured to bracket 108 and extend towards hanger bar 100A on yoke 92A. A wheel 117 is rotatably mounted on the outer end of each of the arms. Two control rods 114A and 116A are slidably mounted in and extend out of valve means 110 to be pivotally connected to arms 114 and 116, respectively, at points eccentric to the point of pivotal connection between the arms and bracket 108. Rods 114A and 116A are spring loaded within valve means 110 to normally yieldably hold the arms 114 and 116 in the horizontal position shown by arm 116 in FIGURE 4. Three conduits, 118, 120 and 122 extend away from valve means 110. The rod 116A and arm 116 are adapted to withhold the flow of hydraulic pressure to conduit or line 118 when arm 116 is in horizontal position shown in FIGURE 4, but are adapted to permit the flow of fluid into the line 118 when arm 116 is depressed as shown in FIGURE 9. The arm 114 and rod 114A are adapted to withhold the flow of hydraulic pressure to lines 120 and 122 whenever arm 114 is in the horizontal position shown in FIGURES 5 and 7; but to permit the flow of fluid under pressure to one of the lines 120 and 122, respectively, when arm 114 is moved either upwardly or downwardly as will be explained hereafter.

A hydraulic conduit or line 124 connects ports 88 and 88A on cylinders 10 and 10A to interconnect compartments 72 and 72A. Line 118 is connected to line 124 to conduct fluid to or from the compartments 72 and 72A. Line 120 extends from valve means 110 to port 82A of

cylinder 10A to convey fluid to and from compartment 74A. Line 120 is also connected to port 78, and hence to compartment 76 in cylinder 40, by line 125. Line 120 is also connected to accumulator 128 by line 130. Accumulators 128 and 132 are comprised of closed tanks 134 into which a sealed expandable diaphragm 136 is inserted. The diaphragms 136 are connected to the incoming hydraulic fluid lines through fittings 138. The tanks 134 normally contain a highly compressible gas such as nitrogen which can be inserted into the tanks through normally closed valves 140. Line 122 extends from valve means 110 to port 82 on cylinder 10 to be in communication with fluid compartment 74. Line 122 is also connected to port 78A on cylinder 40A by line 142 to be communication with compartment 76A. Line 144 connects line 122 with the diaphragm 136 of accumulator 134.

As shown in FIGURES 10 and 11, a rectangular plate 146 with four vertical slots 148 in the corners thereof is mounted on the side of hanger bar 100A adjacent the arm 114 on valve means 110. Plate 146 is secured to bar 100A by four adjustable bolts 150 which extend through the slots 148. Thus, the vertical position of plate 146 can be adjusted on bar 100A by loosening the bolts 150, moving the plate vertically by virtue of slots 148, and then re-tightening the bolts. Similarly, plate 152 having vertical elongated slots 154 is adjustable secured to plate 146 by stud bolts 156 which extend out of plate 146 through slots 154. An elongated vertical shoulder 158 extends outwardly from plate 152 and is of integral construction with the plate. The lower end of shoulder 158 is arcuate to present a cam surface. A second elongated vertical shoulder 160 extends outwardly from plate 146 and is of integral construction with the plate. The upper end of shoulder 160 is arcuate to present a cam surface, and the lower end thereof terminates in tongue 162 which is slidably inserted into slot 164 in shoulder 158, whereby the combined lengths of shoulders 158 and 160, which form a combined cam shoulder designated as 159, can be varied.

A plate 168 having vertical corner slots 170 is adjustably secured to bar 100A by bolts 172 in the same manner as was plate 146, but at a point on bar 100A above plate 146 and vertically opposite arm 116 on valve means 110. A vertical shoulder 174 extends outwardly from plate 146 and is of integral construction therewith. The upper and lower ends of shoulder 174 are arcuate to present a cam surface.

The normal operation of my device is as follows: The pump 106 can be actuated to force hydraulic fluid under pressure through line 112 to valve means 110. Arm 116 on valve means 110 can then be manually depressed to permit fluid to flow into line 118, thence line 124, and thence into the fluid compartments 72 and 72A in cylinders 10 and 10A, respectively. Obviously, arm 116 could be electrically actuated by a solenoid in valve means 110 if the valve were so designed, but since the precise components of valve means are of conventional structure, I have not shown it in great detail. The introduction of fluid into compartments 72 and 72A exerts an upward force on the bottoms of cylinders 40 and 40A, and these cylinders will uniformly rise and support the entire load imposed on the cylinders by the yokes 92 and 92A. When arm 116 is permitted to assume a horizontal position, rod 116A will close to prevent further fluid from entering the conduit 118, and hence the compartments 72 and 72A. If desired, the arm 116 can be moved upwardly to by-pass the pressure port in valve means 110 whereby the weight on cylinders 40 and 40A will force the fluid out of compartments 72 and 72A as these compartments are reduced in volume, whereupon the flow of fluid in this circuit will be reversed and returned directly to oil reservoir 104 by means of a return line 176 extending downwardly from valve means 110 to the reservoir.

The oil well pump mechanism referred to above will require a reciprocal vertical movement of each yoke

92 and 92A. After the yokes have been raised to a satisfactory minimum elevation by introducing fluid into compartments 72 and 72A, the arm 114 on valve means 110 may be in a neutral horizontal position whereby no fluid would be forced into lines 120 or 122, and the elevations of the yokes (and hence, cylinders 40 and 40A) would be fixed by the fluid then in lines 120 and 122 beyond valve means 110. With the cylinder 40 and 40A at the same elevation shown in FIGURE 4 as pump 106 is actuated, arm 116 is pivoted upwardly by cam shoulder 159 (comprised of shoulders 158 and 160) to introduce fluid under pressure into conduit 122, thence through line 142 into compartment 76A, and also into compartment 74. At the same time, fluid moves into the diaphragm 136 of accumulator 132 to cause the diaphragm to inflate and compress the gas within tank 134. Since piston 30A will not move, the introduction of fluid into compartment 76A will force cylinder 40A upwardly. Similarly, since piston 30 cannot move, the introduction of fluid into chamber 74 will cause cylinder 40 to move downwardly. Fluid initially in compartment 74A is thereupon flushed out through conduits 120 and 126 towards compartment 76. This flow of fluid would ordinarily impede the desired result except that the fluid flowing through conduit 120 towards compartment 76 will also be partially exhausted through conduit 120 between conduit 126 and valve means 110 back towards reservoir 104. This discharge of fluid from line 120, in addition to the gas pressure in the tank of accumulator 132, will cause the diaphragm 136 therein to become deflated. Thus, during this cycle of the operation, yoke 92 will be moving downwardly with cylinder 40, and yoke 92A will be moving upwardly with cylinder 40A.

However, as the yoke 92A and hanger bar 100A thereof move upwardly to the degree shown in FIGURE 5, the arm 116 will move out of engagement with cam shoulder 159 and will move into a neutral position wherein no fluid is allowed to flow into or out of lines 120 or 122. However, the great pressure being exerted on the outside of the fluid filled diaphragm 136 by the compressed gas in tank 134 of accumulator 132 will cause fluid to flow out of the diaphragm towards both compartments 76A and 74. Thus, the upward and downward movement of cylinders 40A and 40, respectively, will still continue at a reduced rate of speed. At the same time, the diaphragm 136 in accumulator 128 will start to become inflated because the fluid being flushed out of compartments 76 and 74A cannot return to the reservoir 104. As the diaphragm in accumulator 132 becomes increasingly deflated, and the diaphragm in accumulator 128 becomes increasingly inflated, the accumulator 128 will then take control of the circuit, stop the movement of the cylinders 40 and 40A, and reverse their initial movement whereupon cylinder 40 will start to move upwardly, and cylinder 40A will start to move downwardly. This is accomplished by the gaseous pressure in the tank of accumulator 128 forcing oil out of the then inflated diaphragm therein, wherein fluid will be forced into chambers 74A and 76 to reverse the initial movement of the cylinders. At the same time, the diaphragm in accumulator 132 is beginning to become inflated again.

As the cylinder 40A and yoke 92A move downwardly, cam shoulder 159 again comes into contact with arm 114 to pivot it to the depressed position shown in FIGURE 6. This immediately causes fluid under pressure to flow into line 120 to continue the upward and downward movement of cylinders 40 and 40A, respectively, which was already started by pressurized fluid in accumulator 128.

As the downward movement of cylinder 40A and yoke 92A continues, a cam shoulder 159 disengages arm 114 which moves to its neutral horizontal position in which fluid is prevented from entering or leaving the lines 120 and 122 at valve means 110. At this point, the diaphragm 136 in accumulator 132 becomes inflated as the pressurized fluid in the accumulator 128 continues the movement

5 of the cylinders. Finally, the pressure within the accumulator 132 stops and reverses the movement of the cylinders in the same manner that the pressure in accumulator 128 served this function at the first part of the cycle. The reversal of movement of the cylinders 40 and 40A will cause yoke 92A to rise so that arm 114 is once again elevated by cam shoulder 159 to bring the cycle back to its point of beginning whereupon the cycle will be repeated.

10 The amount of gas in each of the accumulators 128 and 132 can be varied in the adjustment of the cycle. Similarly, the position and length of cam shoulder 159 can be altered in the manner described to provide adjustments in the stroke of the cylinders. If fluid should leak from the lower compartments 72 and 72A so that the minimum elevation of the cylinders 40 and 40A, and the yokes 92 and 92A become less than that initially determined, the cam shoulder 174 will then come into contact with arm 116 as shown in FIGURE 9 whereupon the cylinders 40, 40A, and yokes 92 and 92A will be simultaneously raised in the manner described by the simultaneous introduction of fluid into chambers 72 and 72A. The vertical position of shoulder 174 can be adjusted in the manner described to better control this aspect of the operation.

15 Thus, from the foregoing, it is seen that my device will accomplish at least all of its stated objectives.

Some changes may be made in the construction and arrangement of my Hydraulic Power System for Reciprocal Movement without departing from the real spirit and purpose of my invention, and it is my intention to cover by my claims, any modified forms of structure or use of mechanical equivalents which may be reasonably included within their scope.

I claim:

1. In combination, first and second cylinder units, each cylinder unit comprising, a base cylinder having an open top and a closed bottom portion, a shaft means rigidly secured to the bottom portion of said base cylinder and extending upwardly and outwardly from the upper end thereof, a movable cylinder slidably mounted on said shaft means and having at least one of its ends slidably mounted within said base cylinder, a piston element rigidly secured to said shaft within said movable cylinder to form separate fluid compartments within said movable cylinder above and below said piston element, a first conduit connecting the compartment above said piston in said first cylinder unit to the compartment below said piston in said second cylinder unit, a second conduit connecting the compartment below said piston in said first unit with the compartment above said piston in said second cylinder unit, a hydraulic power means in communication with said first and second conduits, a valve means imposed in said conduits to control the flow of fluid through said conduits towards or away said compartments at different times by said hydraulic power means, and an actuating means on said valve means and in the movable path of one of said movable cylinders whereupon the movement of said one movable cylinder will engage said actuating means to operate said valve means.

2. The structure of claim 1 wherein a third conduit connects the bottom interior portions of said two base means, said third conduit is connected to said hydraulic power means, and a valve is imposed in said third conduit to control the flow of fluid through said third conduit towards or away from said cylinders.

3. The structure of claim 1 wherein accumulators are

imposed in said conduits, said accumulators including means that can yieldably absorb hydraulic pressure.

4. The structure of claim 1 wherein accumulators are imposed in said conduits, said accumulators including means that can yieldably absorb hydraulic pressure, and means within said accumulators for varying the amount of hydraulic pressure said accumulators can absorb.

5. The structure of claim 1 wherein accumulators are imposed in said conduits, said accumulators including means that can yieldably absorb hydraulic pressure, and means within said accumulators for varying the amount of hydraulic pressure said accumulators can absorb; said accumulators being comprised of a closed tank, a sealed diaphragm in each of said tanks in communication with one of said conduits, and a compressible gas within said tanks and outside of said diaphragms.

6. The structure of claim 1 wherein accumulators are imposed in said conduits, said accumulators including means that can yieldably absorb hydraulic pressure, and means within said accumulators for varying the amount of hydraulic pressure said accumulators can absorb; said accumulators being comprised of a closed tank, a sealed diaphragm in each of said tanks in communication with one of said conduits, and means on said tank for adjusting the quantity of compressible gas within said tanks.

7. The structure of claim 1 wherein a cam shoulder is operatively engaged to one of said movable cylinders, and is adapted to engage said actuating means to effect the operation of the actuating means, and means on said cylinder for adjusting the position of said cam shoulder with respect to said movable cylinder.

8. The structure of claim 1 wherein a cam shoulder is operatively engaged to one of said movable cylinders, and is adapted to engage said actuating means to effect the operation of the actuating means, and means on said cylinder for adjusting the length of said cam shoulder with respect to said movable cylinder.

9. The structure of claim 1 wherein a third conduit connects the bottom interior portions of said two base means, said third conduit is connected to said hydraulic power means, and a valve is imposed in said third conduit to control the flow of fluid through said third conduit towards or away from said cylinders, and a second actuating means on said valve means and in the movable path of one of said movable cylinders whereupon the movement of said movable cylinder will engage said second actuating means upon a predetermined degree of movement of said movable cylinder to operate the valve means in said third conduit.

10. In combination, 50
first and second cylinder units, each cylinder unit comprising,
a base cylinder having an open top and a closed bottom portion,
a shaft means rigidly secured to the bottom portion of 55
said base cylinder and extending upwardly and outwardly from the upper end thereof,
a movable cylinder slidably mounted on said shaft means and having at least one of its ends slidably mounted within said base cylinder, 60
a piston element rigidly secured to said shaft within said movable cylinder to form separate fluid compartments within said movable cylinder above and below said piston element,
a first conduit connecting the compartment above said 65

piston in said first cylinder unit to the compartment below said piston in said second cylinder unit,
a second conduit connecting the compartment below said piston in said first unit with the compartment above said piston in said second cylinder unit,
a hydraulic power means in communication with said first and second conduits,
a valve means imposed in said conduits to control the flow of fluid through said conduits towards or away from said compartments at different times by said hydraulic power means,
an actuating means movably secured to said valve means and having three operable positions wherein a first position will cause the flow of hydraulic fluid into only said first conduit, a second neutral position will prevent the flow of fluid into or out of either conduit, and the third position will permit the flow of fluid into only said second conduit,
one of said movable cylinders being a control cylinder, a cam shoulder operatively secured to said control cylinder and being positioned to intermittently engage said actuating means to move said actuating means to said first or said third position,
said actuating means normally being in said neutral position upon being free from engagement with said actuating means,
the flow of fluid through said first conduit being adapted to move said control cylinder in a first direction, accumulators imposed in each of said conduits, said accumulators including means that can yieldably absorb, retain and thence discharge hydraulic pressure, said accumulators absorbing hydraulic pressure when fluid under pressure is introduced into the respective conduits to which said accumulators are secured,
the accumulator in said first conduit having a pressure capacity to discharge hydraulic fluid to continue to move said control cylinder in said first direction after said cam shoulder has released said actuating means from said first position to allow said actuating means to move to said neutral position,
fluid in said second conduit responsive to the displacement of said movable cylinders by the pressure in said first conduit whereby the accumulator in said second conduit will absorb hydraulic pressure as the accumulator in said first conduit discharges hydraulic pressure to continue to move said control cylinder in said first direction, whereupon the movement of said control cylinder will be stopped and reversed as the accumulator in said second conduit absorbs the hydraulic pressure being spent by the discharge of hydraulic pressure from the accumulator in said first conduit, whereupon said control cylinder and said cam shoulder can move into engagement with said actuating means to move said actuating means from said neutral position to said third position.
